UNITED STATES PATENT OFFICE.

MARY A. SMAIL, OF DIME, PENNSYLVANIA.

DESIGN FOR A CHANDELIER-PENDANT.

SPECIFICATION forming part of Design No. 21,543, dated May 17, 1892.

Application filed April 5, 1892. Serial No. 427,943. Term of patent 7 years.

To all whom it may concern:

Be it known that I, MARY A. SMAIL, a citizen of the United States, residing at Dime, in the county of Armstrong and State of Pennsylvania, have invented a new and original Design for Pendent Ornaments for Chandeliers, &c., of which the following is a specification.

The invention relates to a new and original design for decorative pendent ornaments for chandeliers, &c.

The object of the present invention is to provide an attractive decorative pendent ornament for the interior of a room, to be suspended from a chandelier or the like.

The invention resides in a pendent ornament having radially-plaited disks provided at their peripheries with tubular centrally-bulged pendants.

The figure of the drawing is a perspective view of a pendent ornament, showing my new design.

Referring to the drawing, I designates a hanging ornament composed of top and bot-

tom disks 2 and 3 and a larger intermediate disk 4, the disks being centrally connected together. The disks are radially plaited or have the appearance of radial plaits or creases, and hanging in circles from the peripheries of the disks are pendants 5. The pendants 5 are tubular, and each one has a central bulged portion and a series of longitudinal openings. A pendant is arranged on the lower face of the top disk and on that of the intermediate disk in the spaces between the disks. The ornament is attractive and is designed to be suspended from a chandelier, and is of the class known as "air-castles."

What I claim is—

The design for a pendent ornament for chandeliers, as herein shown and described.

In testimony that I claim the foregoing as my own I have hereto affixed my signature in the presence of two witnesses.

MARY A. SMAIL.
